WET PRESS

Benjamin Liebowitz, New York, N. Y., assignor
to Trubenizing Process Corporation, New York,
N. Y., a corporation of New York

Application September 29, 1949, Serial No. 118,657

14 Claims. (Cl. 154—1)

1

In the manufacture of laminated textile articles of wearing apparel comprising two outer plies of cotton textile fabric and an inner ply containing yarns of cellulose derivative, in accordance with the teaching of U. S. Patents Nos. 1,968,409 and 1,968,410, it is the practice in "fusing" to first submit the articles to mechanical pressure without heat while moist with a solvent.

Since most preferred solvents, such as a mixture of acetone and alcohol, are highly volatile at room temperature, it is very desirable in practice that the two actions of moistening and applying mechanical pressure occur simultaneously. The simultaneous application of the solvent and mechanical pressure is usually achieved by use of a device known as a wet press.

The wet presses in general use at present comprise a press having a pair of bucks or platens which are enclosed in a housing; this housing contains a reservoir for the solvent which is fed to the working surface of the bucks or platens by capillary action through cloth wicks which are wrapped around the bucks and extend into the solvent in the reservoir.

This type of wet press, although widely used, has several disadvantages. The principal difficulties are (a) that of obtaining uniform moistening under normal operating conditions, and (b) the limitation of the size of the work or the number of parts which can be simultaneously treated.

In the wet presses in use at present, when the press is closed on the work, solvent is pressed from the padding between the bucks. Some is absorbed by the work, as intended, and the excess drains back through the wicks or drips into the housing. When the press is opened the solvent starts feeding back from the saturated portions of the wicks to those portions of the wicks between the bucks which had been squeezed relatively dry during the pressing cycle. This feeding of the solvent, depending, as it does, on capillarity, is slow, so that under normal operating time-cycles, the rewetting is not uniform; then, if the bucks are more than say five or six inches wide, the time required for re-saturation of the padding is more than the normal interval between cycles, so that the work is improperly moistened.

There are several other disadvantages in the existing types of wet presses which will become more apparent from the statement of the objects of this invention.

One of these objects is to provide an improved wet press of simple construction in which the solvent will be fed to the work surfaces almost

2

instantaneously so that the work surfaces may be made large to accommodate large objects or several small objects simultaneously.

A further object is to provide a wet press which will be more convenient and faster in loading and unloading the work.

Other advantages will be manifest in the course of the description.

The manner in which these advantages are realized will be apparent from the following description of a preferred embodiment of my invention in connection with the illustrations shown in the accompanying drawings, wherein

Fig. 1 is a vertical cross-section of a press embodying my invention shown in open position, with certain features omitted;

Fig. 2 is a diagrammatic section to an enlarged scale of certain portions of the press shown in Fig. 1, with the press still in open position;

Fig. 3 is a diagrammatic section of the press portions shown in Fig. 2, with the press in closed position;

Fig. 4 is a transverse cross-section through the "pan" of the press, when said pan is in the loading position;

Fig. 5 is a transverse cross-section through the pan shown in Fig. 4, when the same is in moistening position;

Fig. 6 is a plan view of the press shown in Fig. 1 in open position;

Fig. 7 is a cross-section corresponding to Fig. 1, showing more fully the arrangement of the parts when the press is in the closed position; and

Fig. 8 is a diagram of the valving and piping for the press.

Referring to the drawings, 1 is a square tubular structural section and 2 is a structural steel channel; these parts are held together at the bottom by a pair of angles 3 to which are transversely fastened steel strips 4 which act as base for the machine.

Fastened to the tubular section 1 and the channel 2 is a pair of steel plates 5 as shown in Figure 6 by means of which the block 6 is attached to the C-shaped member formed by the plates 5. This block 6 is bored to receive a disc 7 which acts as a pressure distributor for transmitting the load to the upper platen or buck 8.

Lips 5a are formed on the plates 5 as shown in Figure 6 by means of which the block 6 is attached to the C-shaped member formed by the plates 5. This block 6 is bored to receive a disc 7 which acts as a pressure distributor for transmitting the pressure to the upper platen

8 through the distributor 7, a screw 9 is employed for which the block 6 is drilled and tapped.

The locknut 10 securely locks the screw 9 in the position in which it has been set. It will be noticed that the end of screw 9 operates in a recess in the distributor 7 so as to allow small angular displacements of the upper platen 8.

The platen 8 itself is held upward against gravity by means of four bolts 11 which are fastened to the platen 8. These bolts pass through openings in the block 6 and co-act with the compression springs 12 and the nuts 13 to support platen 8. In this way the stationary upper platen 8 is mounted so as to have a normal position making an angle of some 40 degrees or thereabouts with the horizontal. The mounting is flexible so as to permit small angular departures from this position about axes lying in the platen as may be required in operation as a result of small inaccuracies in the construction, and at the same time allows only negligible angular movement about the axis perpendicular to the platen.

A cover plate 15 is cut out to receive the block 6 and is mounted on the platen 8 by means of the screws 16 and the compression springs 17 which tend to force the cover plate 15 downward. The downward movement of plate 15 is limited by spacers, not shown in the drawings.

The rim of the cover plate 15 is covered with rubber or other flexible material as shown at 18, the purpose of which is to form a seal, as will be described.

A lower platen 20 is carried on a transverse bar 21 which in turn is fastened to a pair of arms 22 pivoted to the members 5 at 23. Mounted on the lower platen 20 is the pan 24, which is positioned horizontally in the open or loading position of the press as shown in Figure 1. This pan 24 has two rearward extensions 24a (see Figure 6) the purpose of which is to receive the liquid when the press is in the pressing position.

The turning of the lower platen from the loading or open wetting position shown in Figure 1 and Figure 2 to the closed pressing position shown in Figures 3, 5, and 7, is obtained by rotating the arms 22 around the pivot 23 so as to bring the lower platen 20 from the horizontal wetting position shown in Figure 1 into the inclined pressing position of parallelism with the upper platen 8 shown in Figure 3. This rotation is effected by a conventional toggle mechanism composed of the toggle member 25 and 25' which is actuated by means of a pneumatic cylinder 26 whose piston rod 27 is pivoted at 28 to an extension 27a of the toggle member 25.

The two positions of the machine and the various parts thereof are shown most clearly in Figures 1 and 7. The parts are preferably so designed that pressures up to 40 or 50 lbs. per square inch may be applied to the work being moistened.

The liquid with which the work is to be moistened is shown at 30, and is most clearly seen in Figures 2 and 3. When the pan is horizontal, as in Figure 1, the liquid distributes itself over the entire bottom of the pan and thereby wets the padding 31, as shown in Figures 2 and 3.

The padding itself is kept spaced from and above the bottom of the pan by means of a series of bars 32 shown most clearly in Figures 4 and 5. This arrangement permits quick flow of the liquid under the padding so that the same can become

very quickly saturated. The padding itself may be fastened to a perforated metal sheet, not shown in the drawings, so as to distribute the pressure on the padding properly, as will be readily understood by those skilled in the art.

When the press passes from the loading position of Figure 1 to the operating position of Figure 7, the liquid runs down into the extensions 24a. After the moistening operation is completed and the press is opened, the liquid immediately spreads itself over the pan again as shown, e. g. in Figures 4 and 2.

Additional liquid is fed into the pan through flexible piping shown at 33 in Figures 2 and 3, which piping in turn is fed from a liquid level control valve of well known construction.

The system is not unduly sensitive to the liquid level so long as the liquid is high enough to wet the padding 31 in horizontal wetting position and so long as it is not too high to overflow the extensions or receptacles 24a in the inclined pressing position.

Since the padding 31 may become sopping wet with the liquid, it is not desirable to lay the work directly on it, especially since I wish to allow considerable flexibility in the liquid level so that the padding 31 may actually become submerged. Moreover, if the work were laid directly on the padding 31 when the press passes from the closed to the open position, the rapid flow of liquid would cause the work to become sopping wet with the solvent—a condition which the press is expressly designed to avoid.

For this reason, a workholder is provided which is entirely clear of the liquid when the press is in the loading position and which is pushed down into contact with the padding 31 when the press is closed. The upper or working surface of this workholder is shown in Figure 6 and also in Figures 4 and 5.

The workholder comprises a closed broad loop of material like nylon having an upper reach 35 and a lower reach 35a (see Figure 4). The width of the loop is made as wide as the upper platen 8 which determines the maximum size or number of parts which can be handled in one operation.

The loop 35—35a is held taut by means of bars 36 threading the loop at its ends, which bars are carried on short slotted arms 37. There is a pair of such arms 37 at each end of the pan 24, each pair being pivotally mounted on a rod 38 and urged away from each other by the torsion springs 39. It is these torsion springs which keep the loop 35 taut and which allow the workholder to be depressed as required in going from the open to the closed position of the press.

After wetting of the padding 31, the work, e. g. a collar shown at 40 is laid on the surface of the workholder 35. When the platens are brought together by rotating the lower platen from the loading position shown in Figure 1 into the pressing position shown in Figure 7, the upper fixed platen 8 presses against the workholder 35—35a and forces it into the position shown in Figure 5, thereby pressing the work 40 together with the workholder 35—35a against the wetted padding 31, the liquid passing into the work through the fabric loop 35—35a. The pressure between the upper platen and the lower platen, which determines the amount of liquid squeezed out of the padding 31 and into the work, is adjusted by means of the screw 9 which is locked in the desired position by means of the nut 10.

It will be seen from Figures 3, 5, and 7 that when the machine is in the operating pressing

position the cover plate 15 acts as a closure with the help of the rubber lips 18 so that during the pressing operation there is no escape of vapors from the pan. When the press is opened there is some escape of vapors but the nylon workholder proposed by me has the advantage that it retains very little of the solvent after it and the work have been squeezed during the pressing operation.

The angle of turning of the lower platen and quantity of liquid are preferably chosen so that when the press is first being opened, the workholder 35 breaks contact with the upper face of padding 31 before the liquid reaches the padding, so that the workholder is not rewetted while the press is being opened. Furthermore, the workholder nearly fills the opening in the pan and retards the escape of vapors. Moreover, for the purposes intended it is not necessary to use a solvent composed entirely of highly volatile elements.

It has been customary to use as a solvent for the fusing of collars a mixture of 75% acetone and 25% methyl alcohol. It has been found, however, that other less volatile solvent mixtures can be used very satisfactorily, thereby reducing the loss of solvent through evaporation and simultaneously reducing the hazards from the presence of such vapors in the atmosphere.

To minimize shock when the press is lowered from its inclined pressing position to its horizontal open position, a block of rubber may be provided as shown at 41.

The compressed air valving and piping arrangement is shown in Figure 8. This arrangement includes a pair of spaced manually operated three-way valves shown at 42. Normally, these valves 42 shut off the air which is admitted at 43 as shown in Figure 8. They are constructed so that if only one valve is open to the compressed air supply, the air will immediately exhaust out of the other valve and the system will not operate.

It is necessary to operate both valves 42 in order to admit air to the piston-operated valve 44-44a. When both valves 42 are open, air is admitted through the piston-operated valve 44-44a to the bottom of the cylinder 26, thereby pushing its piston upward.

Interposed between the pair of valves 42 and the valve 44-44a is a two-way valve 45 which is normally open, so as not to impede the flow of air to the piston-operated valve 44-44a. When, however, the toggle reaches the extended position of Figure 7, the member 25 operates the valve 45 as shown in Figure 7, thereby trapping the air between valve 45 and the piston-operated valve 44-44a.

Hence, when the press has been closed the operator can release the manually operated valves 42 and the press will stay closed. So long as air pressure is thus kept in the system, the press will remain in the closed position.

In case of emergency the pressure can be released by means of a two-way valve 46 which can be foot-operated or manually-operated as desired. For normal operation a needle valve is provided at 47 which allows air to leak at a controlled rate from the piston-operated valve 44. When the pressure in this valve is sufficiently reduced, it operates to shut off the compressed air supply from the cylinder 26 and at the same time to open the cylinder 26 to the atmosphere.

A quick release valve, as is well known in the art, may be used to facilitate rapid opening of the press.

It has been found by experiments that it is unnecessary to use a padding on the upper fixed platen 8. However, such padding may be used, as is shown in dotted lines at 50.

It will be seen that the work is wetted from one side only unless the padding 50 is used. In the latter case, the padding 50 is kept moist by solvent pressed out of the padding 31. However, I have found that very adequate wetting is obtainable without padding 50.

The amount of moisture left in the work is determined by the pressure, which can be adjusted.

Inspection of the drawings shows how this invention accomplishes its objectives:

In the first place, the wetting of the padding takes place by flooding and is practically instantaneous; the only dependence on capillary action is in the direction of the thickness of the padding, and that path is so short that uniformity of wetting is almost instantaneously achieved. This overcomes one of the main drawbacks of the older types of wet presses and allows the working width to be increased to any desired extent. For example, the machine shown in the drawings is proportioned to accept three ordinary collartops or two one-piece collars for processing in a single operation. The result is a much higher output than the existing type presses can give.

In the second place, in my new press there is no need to insert the work through a narrow slot. The work carrier is readily accessible to the operator who can lay the work on quickly and easily without any inconvenience.

In the third place, the machine is of simple design and construction, leading to relatively low costs of manufacture and ease of maintenance.

What I claim is:

40. 1. In a wet press of the character described the combination comprising a stationary support; a stationary inclined upper platen on said stationary support; a lower platen mounted on said stationary support turnable about a horizontal axis between a horizontal wetting position in which said turnably mounted lower platen is spaced from said stationary inclined upper platen and inclined pressing position in which said turnably mounted lower platen is positioned adjacent said stationary inclined upper platen; a vessel adapted to hold liquid and forming part of said lower platen turnably mounted on said stationary support; a padding mounted also on said turnably mounted lower platen turnably together with the same so as to be wetted by said liquid in said vessel when said turnably mounted lower platen is in horizontal wetting position but to be out of contact with said liquid in said vessel when said turnably mounted lower platen is in inclined pressing position; and operating means associated with said turnably mounted lower platen for tilting the same together with said vessel and padding from horizontal wetting position into inclined pressing position and back.

65. 2. In a wet press of the character described the combination comprising a stationary support; a stationary inclined upper platen on said stationary support; a lower platen mounted on said stationary support turnable about a horizontal axis between a horizontal wetting position in which said turnably mounted lower platen is spaced from said stationary inclined upper platen and inclined pressing position in which said turnably mounted lower platen is positioned adjacent said stationary inclined upper platen; a flat pan

adapted to hold liquid and forming part of said lower platen turnably mounted on said stationary support; a padding mounted also on said turnably mounted lower platen turnably together with the same so as to be wetted by said liquid in said flat pan when said turnably mounted lower platen is in horizontal wetting position but to be out of contact with said liquid in said flat pan when said turnably mounted lower platen is in inclined pressing position; and operating means associated with said turnably mounted lower platen for tilting the same together with said flat pan and padding from horizontal wetting position into inclined pressing position and back.

3. In a wet press of the character described the combination comprising a stationary support; a stationary inclined upper platen on said stationary support; a lower platen mounted on said stationary support turnable about a horizontal axis between a horizontal wetting position in which said turnably mounted lower platen is spaced from said stationary inclined upper platen and inclined pressing position in which said turnably mounted lower platen is positioned adjacent said stationary inclined upper platen; a flat pan adapted to hold liquid and forming part of said lower platen turnably mounted on said stationary support; a padding permanently arranged within said flat pan turnably together with the same so as to be adapted to be wetted by said liquid in said flat pan when said turnably mounted lower platen is in horizontal wetting position but to be out of contact with said liquid in said flat pan when said turnably mounted lower platen is in inclined pressing position; and operating means associated with said turnably mounted lower platen for tilting the same together with said flat pan and padding from horizontal wetting position into inclined pressing position and back.

4. In a wet press of the character described the combination comprising a stationary support; a stationary inclined upper platen on said stationary support; a lower platen mounted on said stationary support turnable about a horizontal axis between a horizontal wetting position in which said turnably mounted lower platen is spaced from said stationary inclined upper platen and inclined pressing position in which said turnably mounted lower platen is positioned adjacent said stationary inclined upper platen; a flat pan adapted to hold liquid and mounted on said turnably mounted lower platen on the top face thereof; a padding permanently mounted within said flat pan turnably together with the same and spaced from the edges thereof so as to be adapted to be wetted by said liquid in said flat pan when said turnably mounted lower platen is in horizontal wetting position but to be out of contact with said liquid in said flat pan when said turnably mounted lower platen is in inclined pressing position; and operating means associated with said turnably mounted lower platen for tilting the same together with said flat pan and padding from horizontal wetting position into inclined pressing position and back.

5. In a wet press of the character described the combination comprising a stationary support; a stationary inclined upper platen on said stationary support; a lower platen mounted on said stationary support turnable about a horizontal axis between a horizontal wetting position in which said turnably mounted lower platen is spaced from said stationary inclined upper platen

and inclined pressing position in which said turnably mounted lower platen is positioned adjacent said stationary inclined upper platen; a vessel adapted to hold liquid and composed of a wetting vessel portion and a storing vessel portion, said vessel mounted on said turnably mounted lower platen turnably together with the same so that in horizontal wetting position of said turnably mounted platen at least said wetting vessel portion contains liquid and in inclined pressing position of said turnably mounted platen only said storing vessel portion contains liquid; a padding mounted within said wetting vessel turnably together with the same portion of said vessel so as to be adapted to be wetted by said liquid in said vessel when said turnably mounted lower platen is in horizontal wetting position but to be out of contact with said liquid in said vessel when said turnably mounted lower platen is in inclined pressing position; and operating means associated with said turnably mounted lower platen for tilting the same together with said vessel and padding from horizontal wetting position into inclined pressing position and back.

6. In a wet press of the character described the combination comprising a stationary support; a stationary inclined upper platen on said stationary support; a lower platen mounted on said stationary support turnable about a horizontal axis between a horizontal wetting position in which said turnably mounted lower platen is spaced from said stationary inclined upper platen and inclined pressing position in which said turnably mounted lower platen is positioned adjacent said stationary inclined upper platen; a flat pan adapted to hold liquid and composed of a wetting pan portion and a storage pan portion, said flat pan mounted on said turnably mounted lower platen turnably together with the same so that in horizontal wetting position of said turnably mounted platen at least said wetting pan portion contains liquid and in inclined pressing position of said turnably mounted platen only said storing pan portion contains liquid; a padding mounted within said wetting pan turnably together with the same portion of said pan so as to be wetted by said liquid in said flat pan when said turnably mounted lower platen is in horizontal wetting position, but being out of contact with said liquid in said flat pan when said turnably mounted lower platen is in inclined pressing position; and operating means associated with said turnably mounted lower platen for tilting the same together with said pan and padding from horizontal wetting position into inclined pressing position and back.

7. In a wet press of the character described the combination comprising a stationary support; a stationary inclined upper platen on said stationary support; a lower platen mounted on said stationary support turnable about a horizontal axis between a horizontal wetting position in which said turnably mounted lower platen is spaced from said stationary inclined upper platen and inclined pressing position in which said turnably mounted lower platen is positioned adjacent said stationary inclined upper platen; a flat pan having side walls and adapted to hold liquid, said flat pan mounted on said turnably mounted lower platen extending parallel to the same; a padding mounted within said flat pan so as to leave a free pan portion between itself and that side wall of the pan which is lowermost when said lower platen is in inclined pressing position; and operating means associated with said turnably

mounted lower platen for tilting the same together with said pan and padding from horizontal wetting position into inclined pressing position and back.

8. In a wet press of the character described the combination comprising a stationary support; a stationary inclined upper platen on said stationary support; a flat pan having two opposite side walls and mounted on said stationary support turnable about a horizontal axis between a horizontal wetting position in which said flat pan is spaced from said stationary inclined upper platen and inclined pressing position in which said flat pan is positioned adjacent said stationary inclined upper platen with one of said side walls of said pan positioned lower than the other; a padding mounted within said turnably mounted flat pan turnably together with the same and spaced from the lower of said side walls of said pan; and operating means associated with said turnably mounted flat pan for tilting the same together with said padding from horizontal wetting position into inclined pressing position and back.

9. In a wet press of the character described the combination comprising a stationary support; a stationary inclined upper platen on said stationary support; a vessel adapted to hold liquid and mounted on said stationary support turnable about a horizontal axis between a horizontal wetting position in which said vessel is spaced from said stationary inclined upper platen and inclined pressing position in which said vessel is positioned adjacent said stationary inclined upper platen; a padding mounted within said turnably mounted vessel turnably together with the same so as to be wetted by said liquid in said vessel when the same is in horizontal wetting position but to be out of contact with said liquid in said vessel when the same is in inclined pressing position; and operating means associated with said turnably mounted vessel together with said padding for tilting the same from horizontal wetting position into inclined pressing position and back.

10. In a wet press of the character described the combination comprising a stationary support; a stationary inclined upper platen on said stationary support; a flat pan adapted to hold liquid and mounted on said stationary support turnable about a horizontal axis between a horizontal wetting position in which said flat pan is spaced from said stationary inclined upper platen and inclined pressing position in which said flat pan is positioned adjacent said stationary inclined upper platen; a padding mounted within said turnably mounted flat pan turnably together with the same parallel to the bottom wall of the same so as to be wetted by said liquid in said pan when the same is in horizontal wetting position, but to be out of contact with said liquid in said flat pan when the same is in inclined pressing position; and operating means associated with said turnably mounted flat pan for tilting the same together with said padding about said horizontal axis from horizontal wetting position into inclined pressing position and back.

11. In a wet press of the character described the combination comprising a stationary inclined upper platen; a flat pan adapted to hold liquid and mounted turnably about a horizontal axis between horizontal wetting position spaced from said stationary inclined upper platen and inclined pressing position coacting with said sta-

tionary inclined upper platen; a padding mounted within said flat pan parallel to the bottom wall of the same so as to be wetted by said liquid in said pan when the same is in horizontal wetting position, but to be out of contact with said liquid in said flat pan when the same is in inclined pressing position; a liquid permeable flat holding member arranged within said flat pan parallel to said padding; resilient mounting means for said liquid permeable flat holding member resiliently holding the same spaced from said padding but permitting movement of said holding member into contact with said padding when pressed against said stationary inclined upper platen; and means associated with said flat pan for tilting the same about said horizontal axis from horizontal wetting position into inclined pressing position and back.

12. In a wet press of the character described the combination comprising a stationary support; a stationary inclined upper platen on said stationary support; a flat pan adapted to hold liquid and mounted on said stationary support turnable about a horizontal axis between a horizontal wetting position in which said flat pan is spaced from said stationary inclined upper platen and inclined pressing position in which said flat pan is positioned adjacent said stationary inclined upper platen; a flat support mounted within said flat pan on the bottom wall of the same provided with openings for passage of liquid therethrough; a padding mounted within said turnably mounted flat pan turnably together with the same on said flat support parallel to said bottom wall so as to be wetted by said liquid in said pan when the same is in horizontal wetting position, but to be out of contact with said liquid in said flat pan when the same is in inclined pressing position; and operating means associated with said turnably mounted flat pan for tilting the same together with said padding about said horizontal axis from horizontal wetting position into inclined pressing position and back.

13. In a wet press of the character described the combination comprising a stationary inclined upper platen; a flat pan adapted to hold liquid and mounted turnably about a horizontal axis between horizontal wetting position spaced from said stationary inclined upper platen and inclined pressing position coacting with said stationary inclined upper platen; a flat support mounted within said flat pan on the bottom wall of the same provided with openings for passage of liquid therethrough; a padding mounted within said flat pan parallel to the bottom wall of the same so as to be wetted by said liquid in said pan when the same is in horizontal wetting position, but to be out of contact with said liquid in said flat pan when the same is in inclined pressing position; a liquid permeable flat holding member arranged within said flat pan parallel to said padding; resilient mounting means for said liquid permeable flat holding member resiliently holding the same spaced from said padding but permitting movement of said holding member into contact with said padding when pressed against said stationary inclined upper platen; and means associated with said flat pan for tilting the same about said horizontal axis from horizontal wetting position into inclined pressing position and back.

14. In a wet press of the character described the combination comprising a stationary inclined upper platen; a flat pan having side walls and adapted to hold liquid, said flat pan mounted

11

turnably about a horizontal axis between horizontal wetting position spaced from said stationary inclined upper platen and inclined pressing position coacting with said stationary inclined upper platen; a flat support mounted within said flat pan on the bottom wall of the same provided with openings for passage of liquid therethrough; a padding mounted within said flat pan on said flat support so as to leave a free pan portion between itself and that side wall of the pan which is lowermost when said flat pan is in inclined pressing position; a liquid permeable flat holding member arranged within said flat pan parallel to said padding; resilient mounting means for said liquid permeable flat holding member resiliently holding the same spaced from said padding but permitting movement of said holding member into contact with said padding

5 when pressed against said stationary inclined upper platen; and means associated with said flat pan for tilting the same about said horizontal axis from horizontal wetting position into inclined pressing position and back.
